UNITED STATES PATENT OFFICE.

PAUL REUTER-LORENZEN, OF DETROIT, MICHIGAN.

PORTABLE COMBINED MANTEL, FIREPLACE, AND HEARTH UNIT.

Application filed May 8, 1925. Serial No. 28,900.

To all whom it may concern:

Be it known that I, PAUL REUTER-LORENZEN, a subject of the King of Denmark, residing at Detroit, in the county of Wayne 5 and State of Michigan, have invented certain new and useful Improvements in Portable Combined Mantel, Fireplace, and Hearth Units, of which the following is a specification.

10 The invention relates to a portable combined mantel, fireplace and hearth unit capable of being positioned and secured within a room for not only ornamenting the same, but further for use for electric heaters, but 15 it is to be understood that the fireplace of the unit can be employed for any form of heater for which it is found applicable, and the invention has for its object to provide, in a manner as hereinafter set forth, a unit 20 of the class referred to, having means for imparting thereto the appearance of being constructed of brick and further to provide a unit with a fire-proof hearth and fireplace without the employment of fire bricks 25 or fire clay in its construction.

A further object of the invention is to provide, in a manner as hereinafter set forth, a unit of the class referred to, having means for coupling it to the studs or wall and 30 sub-floor of a room of a building, and further imparting to the unit the appearance of being constructed from tile or brick.

Further objects of the invention are to provide a portable combined mantel, fireplace and hearth unit, in a manner as hereinafter set forth, and which is simple in its 35 construction and arrangement, strong, durable, compact, readily assembled, thoroughly efficient in its use, conveniently secured in position within a room, fire resisting, and comparatively inexpensive to manufacture.

With the foregoing and other objects in view, the invention consists of the novel construction, combination and arrangement 40 of parts, as hereinafter more specifically described and illustrated in the accompanying drawings, wherein is shown an embodiment of the invention, but it is to be understood that changes, variations and modifications 45 can be resorted to which come within the scope of the claims hereunto appended.

In the drawings wherein like reference characters denote corresponding parts throughout the several views:—

Figure 1 is a front elevation of a com- 55 bined mantel, fireplace and hearth unit, in accordance with this invention.

Figure 2 is a section on line 2—2, Figure 1.

Figure 3 is a section on line 3—3, Figure 1.

Figure 4 is a section on line 4—4, Figure 2. 60

Figure 5 is a fragmentary view, in elevation, of the form of galvanized metal lath employed as one of the sections of the unit.

A combined mantel, fireplace and hearth 65 unit, in accordance with this invention, comprises a frame formed of two pair of spaced front standards. The standards of each pair are arranged in spaced relation and the standards of one pair are indicated at 1, and 70 the standards of the other pair at 2. The inner standards of one pair oppose the inner standard of the other pair, and the distance between the standards of each pair is greater than the distance between the inner standards of the pairs of standards. The outer standard of each pair is of greater 75 height than the inner standard of each pair. Mounted on the upper ends of the inner standards of said pairs and extending from 80 the outer standard of one pair to the outer standard of the other pair is a flat cross bar 5, which is rectangular in cross section. Mounted on the cross bar 5, at a point 85 between its transverse center and each end thereof, is an upright support. These supports are indicated at 7, 8, and have their upper ends in alignment with the upper ends of the outer standards 1, 2. Arranged rearwardly with respect to the outer standards 1, 2, as well as being spaced therefrom, is a pair of back standards 1, 2. Mounted on the upper end of the outer standards 1, 2 is a front top bar 11. Mounted on the standards 9, 10 and fixed 90 to the bars 11 are side bars 13. The standards and bars are suitably secured together to provide the frame.

Secured between the standards 9 and 10 is an angle iron 15, through which is adapted 100 to extend suitable hold-fast devices, not shown, to secure the unit against the wall of the room or to the wall studs. One or more angle irons 15 can be employed. The wall is indicated at 16 and the studs therefor at 17. Secured to the lower end of each of the front standards and projecting forwardly therefrom is an angle iron 18,

through which is adapted to extend hold-fast devices 19 for securing the unit to the sub-floor 20 of the room. The hold-fast devices for securing each of the angle irons 5 to a front standard are indicated at 21.

The standards 1, 2, 7, 8, 9 and 10 are rectangular in cross section. The standards 1, 2 have their sides disposed at right angles with respect to the sides of the standards 7, 10 8, 9 and 10. The standards 7 and 8 align with each other and have their sides positioned at right angles with respect to the standards 1, 2. The outer sides of the outer standards 1, 2 are in alignment with the 15 outer edges of the standards 9, 10.

Secured to the rear edge and inner side of the inner standard 1 and the inner standard 2 and also to the intermediate portion of the rear edge and intermediate 20 portion of the lower face of the cross bar 5 is an asbestos sheeting 22.

A galvanized metallic lathing 24 is secured to the front side of the cross bar 5, the forward edges of the standards 1, 2, 25 the outer sides of the outer standards 1, 2, the outer edges of the standards 9, 10, the forward side of the standard 11, and also against the asbestos sheeting which is positioned against the inner sides of the inner 30 standards 1, 2, and the intermediate portion of the lower face of the cross bar 5. The metallic lathing 24 is secured in any suitable manner, preferably by nailing to the standards and cross bar. The metallic lathing 35 24 is cut away to form clearances for the vertical legs of the angle irons 18. The asbestos sheeting 22 and metallic lathing 24 are suitably secured together.

Applied to the outer face of the metallic lath 24 is a covering 25 formed of a magnesite composition of the desired thickness, having a roughened surface. Applied to the outer face of the covering 25 is a coating 26 of a magnesite composition which is 40 colored similar to the color of mortar and of less thickness than the covering 25. Applied to the outer face of the coating 26 is a coating 27 formed from a magnesite composition and which is of the color of the 45 brick or tile which is to be imitated. The surface of the coating 27 is either smoothed or combed and then provided with suitable furrows of sufficient depth to show the coating 26, whereby the outer surface of the 50 coating 27 will have exactly the same appearance as a brick or tile surface.

The inner standards 1, 2 and cross bar 5 are so arranged relatively to each other to provide a fireplace 28.

Arranged within the fireplace 28 and projecting rearwardly from the inner standards 1, 2 and cross bar 5, is an open front and bottom fire box 23 formed of sheet iron and provided with turned edges or flanges 23', 23'', which abut against the asbestos sheet-

ing 22 at the rear edges of the inner standards 1, 2 and rear side of the cross bar 5 and are fixedly secured thereto. The bottom of the box 23 is closed by the hearth of the fireplace. The lower face of the top 70 of the fire box 23, as well as the outer faces of the sides thereof and forward face of its back has the metallic lathing 24 extended throughout thereof and with the lathing coated throughout with the covering 25 and 75 coating 26.

The hearth of the fireplace is constructed from a base of sheet metal 29, having arranged thereon a metallic lathing 30, against which is positioned a covering 31, formed 80 from a magnesite composition and which has suitably embedded therein, from the top thereof, a tiling 32. The metallic sheet 29 together with the elements arranged therein extends forwardly from the back wall of 85 the fireplace to a point a substantial distance from the front of the fireplace and also from the coating 27 at each side of the fireplace, and the outer side edges and forward edge of the elements 29, 30, 31 and 32 are enclosed by bevelled strips 33.

Mounted against the top of the upper face of the coating 27 and extending entirely across the same, as well as projecting therefrom, is a beading 34, which is suitably secured in position and projects a substantial distance forwardly with respect to the coating 27. Mounted on the top of the bars 11 and 13, as well as on the top of the beading 34, is a rectangular, flat top member 100 35 forming a mantel-piece.

A combined mantel, fireplace and hearth as aforesaid, provides a fireplace and hearth which is absolutely fire-proof and which is set up without the employment of fire brick 105 or fire clay in its construction, and further whereby the hearth is a firm part of the mantel. Then, furthermore, the unit when set up appears as being constructed from brick or tile. After the unit has been constructed, it is transported to the house where it is to be used and is secured in the desired position within the room of the house, through the medium of the angle-shaped members 15 and 18 in connection with the 110 hold-fast devices extending therethrough, and it is thought that the many advantages of a unit of the class referred to and in accordance with this invention, can be readily understood, and although the preferred 115 embodiment of the invention is as illustrated and described, yet it is to be understood that changes in the details of construction can be had which fall within the scope of the invention as claimed.

What I claim is:—

1. A unit of the class referred to comprising a frame, an asbestos sheeting arranged around the inner edges at the intermediate portion of the front of the frame, a metallic 130

lathing secured throughout to the front of the frame further connected to said asbestos sheeting, said metallic lathing further extended into the intermediate portion of the frame to provide a fireplace, a covering of a magnesite composition throughout the outer face of the lathing, a coating of a magnesite composition applied to the outer face of said covering and of the color of mortar, a suitably colored furrowed coating of magnesite composition applied to the outer face of the first mentioned coating, a head element mounted on the frame, and coupling members carried by the frame for the passage of hold-fast devices therefor.

2. A unit of the class referred to comprising a frame, an asbestos sheeting arranged around the inner edges at the intermediate portion of the front of the frame, a metallic lathing secured throughout to the front of the frame and further connected to said asbestos sheeting, said metallic lathing further extended into the intermediate portion of the frame to provide a fireplace, a covering of a magnesite composition throughout the outer face of the lathing, a coating of a magnesite composition applied to the outer face of said covering and of the color of mortar, a suitably colored furrowed coating of magnesite composition applied to the outer face of the first mentioned coating, a head element mounted on the frame, coupling members carried by the frame for the passage of hold-fast devices therefor, and a hearth for said fireplace consisting of a metallic sheet having interposed thereon a metallic lathing ex-

tending into a magnesite composition having tiles embedded in the top thereof.

3. A unit of the class described comprising a mantel having as an inherent part thereof a fireplace, said fireplace having the walls thereof consisting of a metallic lathing, a covering of a magnesite composition for said lathing, a mortar colored coating for said covering, and a suitably colored furrowed coating for the first mentioned coating.

4. A unit of the class described comprising a mantel having as an inherent part thereof a fireplace, said fireplace having the walls thereof consisting of a metallic lathing, a covering of a magnesite composition for said lathing, a mortar colored coating for said covering, a suitably colored furrowed coating for the first mentioned coating, and a hearth for said fireplace formed of a metallic sheet provided on its upper face with a metallic lathing extending into a composition of magnesite having tiling embedded in the top thereof.

5. A unit of the class described comprising a mantel having as an inherent part thereof a fireplace, said fireplace having the walls thereof consisting of an inner metallic lathing, an outer covering of a magnesite composition for said lathing, a mortar colored coating for said covering, a suitably colored furrowed coating for the first mentioned coating, and said mantel further including a supporting frame for said lathing.

In testimony whereof I affix my signature hereto.

PAUL REUTER-LORENZEN.
